(74) Attorney, Agent, or Firm — Ward and Smith, P.A.;
Ryan K. Simmons(57) **CLAIM**

The ornamental design for an infant pod, as shown and described.

DESCRIPTION

FIG. 1 is a perspective view of an infant pod showing a new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The dashed lines are included for the purpose of illustrating portions of the infant pod that form no part of the claimed design.
